PUZZLE

Hansel King Riddle, Albuquerque, N. Mex.

Application April 21, 1953, Serial No. 24,598

Term of patent 14 years

(Cl. D34—15)

To all whom it may concern:

Be it known that I, Hansel King Riddle, a citizen of the United States of America, residing at Edgewood Star Route, Albuquerque, New Mexico, have invented a new, original, and ornamental Design for a Puzzle, of which the following is a specification, reference being had to the accompanying drawing forming a part hereof.

Figure 1 is a perspective view of a puzzle embodying my new design,

Figure 2 is a perspective view thereof rotated substantially forty-five degrees and tilted in a slightly different position,

Figure 3 is a side elevational view thereof, and Figure 4 is a side elevational view thereof taken at right angles to Figure 3.

I claim:

The ornamental design for a puzzle, as shown.
